CLAIM

We claim the ornamental design for an air-fry basket, as shown and described.

DESCRIPTION

FIG. 1 is a first top perspective view of an air-fry basket of the present disclosure;

FIG. 2 is a first bottom perspective view of the air-fry basket of FIG. 1;

FIG. 3 is a first side elevational view of the air-fry basket of FIG. 1;

FIG. 4 is a second side elevational view of the air-fry basket of FIG. 1;

FIG. 5 is a front elevational view of the air-fry basket of FIG. 1;

FIG. 6 is a rear side elevational view of the air-fry basket of FIG. 1;

FIG. 7 is a top plan view of the air-fry basket of FIG. 1; and, FIG. 8 is a bottom plan view of the air-fry basket of FIG. 1. The broken lines depict portions of the article that form no part of the claimed design.
